UNITED STATES PATENT OFFICE.

WILFRED WHITELEY AND WALTER SPENCER, OF ELLAND, ENGLAND.

COOLING-TANK.

1,113,921.

Specification of Letters Patent. Patented Oct. 13, 1914.

Application filed July 8, 1913. Serial No. 777,874.

To all whom it may concern:

Be it known that we, WILFRED WHITELEY and WALTER SPENCER, subjects of the King of Great Britain, residing at Elland, in the county of York, England, have invented new and useful Improvements in and Relating to Cooling-Tanks, of which the following is a specification.

This invention relates to cooling apparatus for cooling hot water from several separate sources at the same time, such as from the cylinder jackets in internal combustion engines and from the scrubber in a suction gas plant. By our improved means hot water from these sources is separately cooled and returned to separate compartments in a cold water supply tank for subsequent use.

Our invention is also adapted for use in connection with the supply of cold water to the scrubbers of suction gas plants and to the cylinder jackets of internal combustion engines. It will, however, be obvious that our apparatus is equally serviceable for cooling supplies from other sources and that such water when cooled may be returned to separate tanks or compartments or a common tank or the like as desired.

In the drawings: Figure 1 is a vertical sectional view of our device, and Fig. 2 is a sectional plan of the cooling cylinder.

In the drawings like reference characters denote like parts throughout.

A is a cylindrical casing divided longitudinally into three compartments B, C, and D, an exhaust outlet E being provided at the bottom of the central compartment C. The casing A is supported by a cold water supply tank F shown in this particular instance as having two compartments G and H. The two side chambers B and D serve to cool the water from the engine cylinder jacket and the scrubber respectively or as the case may be from any other two sources, while the central chamber or compartment C is provided for the purpose of condensing any vapor which may accumulate in the upper portion of the chambers B and D. The chambers B and D communicating with the compartments G and H respectively of the cold water supply tank F over which they are arranged through perforations J in the cover K. The condensation from the central chamber C descends into the compartment H of the tank F through the medium of a water sealed pipe L.

The chambers B, C and D of the casing A

are provided at suitable intervals with a plurality of wooden grids or baffle plates I for a purpose hereinafter to be set forth. The partitions M which divide the chamber 60 A into compartments terminate short of the top permitting of a direct communication of the chambers.

Water drawn from the tank F is circulated through the engine cylinder jacket by 65 the pipe N and pump P and to its cooling chamber B or D as the case may be through pipe R. Cold water may be supplied to a certain source by the pipe S and pump T and returns therefrom by pipe U and pump V. 70 The pipes U and R terminate in perforated ends W by means of which the water returning through said pipes is sprayed over the upper portion of the chambers B and D. A fan X is provided which drives a blast of 75 air through pipe Y into the tank F above the water level thereof, upwardly through perforations J and chambers B and D cooling the descending hot water in its passage. The separate air currents in these two chambers converge and enter the central chamber 80 C at the top and descend through said chamber and pass out at exhaust E. The condensation which is caught at the bottom of the chamber C enters either chamber G or H 85 as may be desired through the pipe L.

It will be seen that the apparatus provided allows of the quick and effectual cooling of a continually running supply of hot water from two or more sources and keeping 90 these sources separate. It will also be seen that taking for instance the case of the scrubber and gas engine any injurious matter as a chemical provided by the washing of the gas and mixing with the water used 95 in the scrubber, would be kept separate and not injure the engine cylinder or its jacket.

Having now described our invention what we claim and desire to secure by Letters Patent is:

A cooling apparatus comprising a casing having a plurality of partitions forming central and side compartments, baffle plates in said compartments, a tank arranged below said casing, compartments formed in 105 said tank, a pipe connecting one of said compartments with the lower end of the central compartment of said casing, the bottom of said central compartment being closed against the admission of air, a bottom provided with openings for said casing, said 110 openings being disposed beneath said side

compartments, means for introducing a current of air to said tank, an exhaust in said central compartment, and means for introducing hot water to the upper ends of said side compartments, as and for the purpose specified.

In testimony whereof we have signed our

names to this specification in the presence of two subscribing witnesses.

WILFRED WHITELEY.
WALTER SPENCER.
